GAME OF SKILL

John H. Keeney, Chicago, Ill.

Application October 6, 1931, Serial No. 567,232

6 Claims. (Cl. 273—121)

This invention relates to certain novel improvements in a game of skill, and has for its principal object the provision of an improved construction of this character which will be entertaining in use and economical to manufacture.

It is an object of this invention to provide a new and entertaining game of skill.

Other objects of the invention are to provide an improved and entertaining game of skill embodying the use of balls; to provide a novel arrangement of ball-receiving scoring pockets; and to enhance the interest of the player by promoting the element of chance and personal skill.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a top plan view of a preferred construction of the invention;

Fig. 2 is a longitudinal sectional view on line 2—2 in Fig. 1;

Fig. 3 is a transverse sectional view on line 3—3 in Fig. 2;

Fig. 4 is a bottom plan view, partly in section, on line 4—4 in Fig. 2;

Fig. 5 is a sectional view on line 5—5 in Fig. 4;

Fig. 6 is a sectional view on line 6—6 in Fig. 5;

Fig. 7 is a sectional view on line 7—7 in Fig. 4;

Fig. 8 is a sectional view on line 8—8 in Fig. 5;

and

Fig. 9 is a sectional view on line 9—9 in Fig. 8.

In the drawings, which illustrates a preferred and practical embodiment of the invention, 10 indicates generally a cabinet supported on legs 11. Included in the cabinet 10 is top panel 12 in which is a transparent plate 13.

Arranged below the transparent plate 13 is a member 14 which provides a playing surface on which balls, such as 15, are played in a manner to be described hereinafter. Leading from a ball receiving chamber 17 provided in the cabinet onto the playing

surface 14 is a ramp 16 (Figs. 3 and 7), the base 18 of which is continuous with the inclined base 19 of the ball-receiving chamber 17 (Fig. 7). Mounted in plates 20 on the cabinet is a guide 22 in which a plunger or ball-projecting element 23

50 is slidable, said element having a head 24 that is movable over the inclined base 19 of the ball-receiving chamber. A spring 25 is provided on the element 23 between the head 24 and the plate 21, to urge the head 24 against the ball 15 when the player grasps the handle 26 and retracts the

element 23 to compress the spring 25 whereby the ball 15 will be projected over the inclined base 19 of the ball-receiving chamber 17 up into the ramp 16 and thence out onto the playing area 14. A bumper 27 is preferably provided on the transparent plate 13 at the point (Fig. 7) where the base 19 of the ball-receiving chamber opens into the ramp 16 to prevent damage to the plate 13 by the impact of the ball. As the ball emerges from the ramp 16 it may be directed by a curved wall or bank 28 in the direction of the arrows 29 (Fig. 1) and may strike a stop 30 whereby the ball will rebound in the direction of the arrow 31 and, depending upon the skill with which the ball-projecting element 23 has been manipulated by the player, the ball may be caused to rebound over into the marked off portion 32 of the area 14, or it may remain outside thereof in the area 14. The base 14, on the upper surface of which the area is defined, is inclined toward the head end 60 of the cabinet, Fig. 1, whereby when the ball is directed up out of the ramp 16 into the area 14 but has not sufficient momentum to travel to the stop 30, or when the ball is deflected by the latter onto the area 14, the ball will run down the area 65 14 into one of the ball-receiving pockets 33 which may be marked with any desired scoring values.

When the ball 15 is in one of the pockets 33 it rests upon a trap 34 that is hinged to the member 14, as at 35. Adapted to release the trap 34 and thereby discharge the balls onto an inclined runway 36 that directs the balls through inlet 62 to the ball receiving chamber 17 is a spring-urged slideable rod 37. Rod 37 has an enlarged portion 53 that is bored to receive a rod 52 that extends through this portion 53 below the trap 34 (Figs. 4, 5, and 8). On the end portions of rod 52 are coil bumper springs 54. Each of these springs 54 has one end attached to the rod 52 and each of these springs (Fig. 8) bears against a depending cam face 56 on the trap 34. When the slide rod 37 is moved to the left (Figs. 2, 4, and 5) the trap 34 drops by gravity to discharge the balls from the pockets 33 onto the runway 36. This movement of rod 37 tensions a spring 55 which has one end fixed below the member 14 and its other end attached to a rod 51 that is similar to rod 52. When the slide rod 37 is released the spring 55 returns the rod 37 to its initial position and the springs 54 on rod 52 bear against the cam faces 56 on the trap 34 and close trap 34 while similar springs on rod 51 close those traps 48 that are arranged laterally from rod 37.

The rod 37 is coin controlled and a suitable coin controlled mechanism therefor is indicated 110

diagrammatically at 38, but is not illustrated in detail since the same forms no part of this invention, whereby in order to operate the rod 37 and discharge the balls 15 onto the runway 36 to the ball-receiving chamber a coin must be paid into the mechanisms 38.

The plunger 23 acts as a gate to control the inlet 62 from the inclined runway 36 to the ball-receiving chamber 17 into which a ball may pass each time the plunger 23 is retracted into ball-projecting position.

Arranged at intervals on the area 14 are obstacles such as pins 39 which are adapted to deflect the ball from a straight course as it rolls down the area 14 toward the pockets 33 whereby to increase the scoring hazard of the ball.

The highest scoring values are marked in concentric circular areas or ball receiving pockets 40 arranged at various points within the diamond 32 (Fig. 1). Each of these circular areas or pockets is defined by an outer upstanding wall 41 on the member 14, which is continuous with a row of pickets 42. In the row of pickets a gap 43 is formed to provide a ball inlet to the outer circle or pocket (Fig. 1). Arranged within each outer circle is an upstanding wall 44 in which is provided a ball inlet 45 that is closed by a swinging door 46 that is mounted on brackets 47 provided on the casting 49.

Skill is required to manipulate the ball projecting element 23 so as to direct the ball from the ramp 16 directly, or from the stop 30, into the entrance 43 from which the ball may roll around the outer circle or pocket or, passing through swinging door 46, enter the inner circle or pocket; but in either event the ball will come to rest upon the trap 48 which is hinged as at 50 to the casting 49 (Figs. 5 and 6) that includes the upstanding walls 41 and 44.

When the rod 37 is slid to the left (Figs. 2, 5 and 6) the traps 48 that are arranged axially of the rod 37 drop by gravity and when the rod 37 is returned by spring 55 to its initial position the traps 48 that are arranged axially along the rod 37 are closed by springs on the rods 57 that are similar to the springs 54 on the rod 52 (Figs. 8 and 9).

The coin control mechanism 38 includes a slide bar 58. A spring 59 has one end attached to the slide bar 58 and its other end fixed to a pin 60 which projects from a housing or bearing 61 for the rod 37; said housing being attached to the cabinet 10.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A game apparatus, comprising a member providing a playing surface, ball-receiving pockets arranged on said playing surface, a pivotal gravity-operated trap arranged under each of said pockets, said traps being hinged to said member, a ball-receiving chamber having an inlet, a ramp leading from said chamber to the playing surface, a runway to conduct the balls from said traps to said inlet, slidable ball-pro-

jecting means in said chamber providing a gate normally closing said inlet, and a slidable mechanism for closing the traps said mechanism normally retaining said traps in closed position against the attraction of gravity.

2. A game apparatus, comprising a member providing a playing surface, ball-receiving pockets arranged on said playing surface, a pivotal gravity-operated trap arranged under each of said pockets, said traps being hinged to said member, a ball-receiving chamber having an inlet, a ramp leading from said chamber to the playing surface, a runway to conduct the balls from said traps to said inlet, slidable ball-projecting means in said chamber providing a gate normally closing said inlet, and a mechanism for closing said traps, said mechanism normally retaining said traps in closed position against the attraction of gravity, said mechanism including a slidable member, members carried by and projecting laterally from said slidable member, and spring members on said laterally projecting members having portions bearing against said traps to hold the same in closed position.

3. A game apparatus, comprising a member providing a playing surface having ball outlets arranged therein, a pivotal gravity-operated trap arranged at each of said outlets, said traps being hinged to said member, a ball-receiving chamber having communication with said playing surface, a runway for conducting balls from said outlets to said chamber, ball-projecting means in said chamber, and a mechanism for closing said traps, said mechanism normally retaining said traps in closed position against the attraction of gravity.

4. A game apparatus, comprising a member providing a playing surface having ball outlets arranged therein, a pivotal gravity-operated trap arranged at each of said outlets, said traps being hinged to said member, a ball-receiving chamber having communication with said playing surface, a runway for conducting balls from said outlets to said chamber, ball-projecting means in said chamber, and a mechanism for closing said traps, said mechanism normally retaining said traps in closed position against the attraction of gravity, said mechanism including a slidable member and members carried by and projecting laterally from said slidable member having springs thereon bearing against said traps to retain the same in closed position.

5. A game device of the type described comprising a board having thereon a plurality of numbered compartments, traps forming part of the floor of each compartment, a cam extending downwardly from each trap, a member adapted to bear against said cams to hold the traps closed and movable relative to said cams to allow the traps to open.

6. A game device of the type described comprising a board having thereon a plurality of numbered compartments, traps forming part of the floor of each compartment, a cam extending downwardly from each trap, a member mounted beneath the traps and extending longitudinally of the game board, horizontally extending bars mounted on said member and extending at right angles thereto and adapted to contact with said cams to hold the traps closed and being movable relative to said cams to allow the traps to open.

JOHN H. KEENEY.
